DOORSTOP

Adolph L. Moberg, Des Moines, Iowa, assignor of
one-half to Edward Hraha, Des Moines, Iowa

Application June 25, 1941, Serial No. 339,626

1 Claim. (Cl. 292—230)

The object of my invention is to provide a door stop of simple, durable and inexpensive construction which may be readily and easily applied to a door and readily and easily adjusted, so that when in operating position it will engage a floor with such accurate adjustment as to slightly flatten the flexible resilient friction wheel against the floor to thereby stop movement of the door in either direction.

A further object is to provide a door stop of this class in which the stop wheel, when in either its operative or inoperative position, is conveniently accessible to an operator's foot, whereby it may be readily and easily moved from one position to the other, and when in inoperative position it will be yieldingly held against accidental movement to its stop position.

Referring to the accompanying drawing—

Figure 1 shows a side elevation of my improved door stop applied to a door and in its inoperative position;

Figure 2 shows a similar view with the stop in operative position;

Figure 3 shows a front elevation of same;

Figure 4 shows a top or plan view of same; and

Figure 5 shows a sectional view on the line 5—5 of Figure 1.

My improved stop comprises a bracket of simple and inexpensive construction. It has a smooth straight upright portion 10 to be placed flat against a door 11, and two integral outwardly extended parallel arms 12.

The bracket is applied to a door for delicate vertical adjustment by means of a metal clip 13 having its ends shaped to engage a door and be secured thereto by screws 13a and its central portion shaped to slidably receive the upright bracket member 10. A set screw 14 is seated in the clip to engage the part 10.

The stop wheel 15 is made of yielding resilient material, such as rubber, and has a wide tread portion and is mounted between the arms 12. It is pivotally connected to the arm by a bolt 16 extended through the arms and also through the wheel 15 at a point eccentric to the wheel.

At the inner upper edges of the arms 12 I have formed inwardly extended projections 17 shown in Fig. 5. It is important that the positions of these projections and the relative position of the wheel 15 be coordinated so that when the wheel is turned to its inoperative position, the wheel will, when approaching inoperative position, have its sides engage the projection and be partially compressed thereby to yieldingly

hold the wheel against accidental movement to operative position.

It is also of importance that when the stop wheel is in its inoperative position, as shown in Fig. 1, a large portion of the upper outer surface of the stop wheel be exposed beyond the bracket for the double purpose of permitting an operator with his foot to press the stop wheel against the projection 17 for yieldingly holding it in inoperative position or to engage it with his foot and move it to operative position; and it is just as important that when the stop wheel is in its operative position, as shown in Fig. 2, the lower outer portion of the stop wheel be exposed beyond the outer end of the bracket arms so that an operator may with his foot readily and easily move it to inoperative position.

The relative size of the stop wheel, the relative length of the arms 12 and the relative positioning of the pivot bolt 16 are of vital importance to the successful operation of my door stop, and must be such that as the stop wheel moves to operative position it will move past a vertical central line through the pivot point and the center of the stop wheel, so that during this movement the stop wheel will be compressed and form a relatively flat surface resting against the floor. By this means the stop wheel yieldingly holds the door against movement in one direction, to the left as shown in Fig. 2. These relative proportions must also be such that when the stop wheel is in said position its inner surface will engage the bracket member 10 below a horizontal line through the pivot and be held thereby against rotation in the direction required for moving the door toward the right, as shown in Fig. 2.

It will be seen that in order to apply the device to a door a very delicate and accurate positioning of the door stop to a door is necessary, and I have provided for such adjustment by means of the clip 13 and set screw 14. In this manner an unskilled operator may secure the device to a door by the screws 13a, and then the bracket may be vertically adjusted by a so-called "fit and try" procedure to determine the action of the stop wheel by the floor so that it is moved to the position shown in Figure 2.

In practice I have found that in many instances it is desirable to hold a door in partially opened position when it is subjected to pressure in both directions by the wind or otherwise, hence, it is highly desirable that the door be held in both directions. I have also found that when a door is being opened and some shock

or jar is applied thereto, that the stop wheel is thereby moved to operative position, which is highly objectionable, and for this purpose I have provided the projections 17 engaging the yielding sides of the stop wheel which have effectively prevented such accidental movement. I have also demonstrated that it is very advantageous to readily, quickly and easily move the stop wheel to any of its positions by a convenient and easy operation of the operator's foot, preventing the necessity of the operator stooping over and using his hands.

I claim as my invention:

A floor engaging door stop comprising a supporting bracket having an elongated flat body portion attachable to a door and a pair of flat arms adjacent the lower end portion thereof extending laterally therefrom, said arms having inward projections adjacent their upper edges, a pivotal support mounted in the free ends of said arms above the lower end of said body por-

tion, a resilient friction wheel for engaging a floor mounted eccentrically on said support between said arms and having its sides closely adjacent the opposed sides of said arms, the distance from the axis of said support to the lower end of said body portion being substantially greater than the radius of said wheel and less than that from the high point of said wheel so that on opening the door the high point of the wheel engages the floor, passes toward the door through a vertical plane longitudinal of the axis of the pivotal support until the periphery of the wheel engages the lower end portion of the bracket to prevent further turning of the wheel to stop the door, and closing the door is resisted in reverse movement, the sides of the wheel when turned upwardly and towards the bracket engaging said projections to hold the wheel in inoperative position.

ADOLPH L. MOBERG.
